TAGE GEORG NYBORG, OF WORCESTER, ENGLAND, ASSIGNOR OF ONE-HALF TO MARK
FREDERICK HIGGINS, OF WORCESTER, ENGLAND

SHAKER CONVEYER

Application filed April 13, 1931, Serial No. 529,828, and in Great Britain May 2, 1930.

This invention relates to shaker conveyers and relates more particularly to that type of conveyer in which the reciprocations of the conveyer are derived from a rotary member 5 through a crank and connecting rod mechanism.

In this type of mechanism, the obliquity of the relatively short connecting rod gives rise to considerable difference in the acceleration 10 at the two ends of the stroke of the conveyer.

In a usual construction, the end of the connecting rod remote from the crank pin only reaches its maximum velocity after two 15 thirds of the forward stroke which means that the forward acceleration is of much lower value than the subsequent deceleration, and conversely in the return stroke the initial increase in speed is sharp and the 20 subsequent decrease in speed more gradual.

For the practical operation of the shaker conveyer it is desirable to ensure that the deceleration at the end of the forward stroke of the conveyer shall be sharp enough to ensure 25 dislodgment of the material i. e. shall exceed the friction of the material on the trays.

According to the present invention, the period of maximum velocity and value of 30 deceleration at the end of the forward stroke is increased by providing in the mechanism a certain amount of loose motion or "slogger" between the cross-head which derives its reciprocation direct from the connecting rod 35 and the member which is connected to the conveyer.

Incidentally, this provision will slightly diminish the value of acceleration at the beginning of both strokes (which is a favourable 40 circumstance) and will also slightly increase the value of the deceleration at the end of the return stroke; but this latter increase owing to the extended duration of this deceleration may be neglected.

The invention is illustrated in the accompanying drawing in which the sole figure illustrates an embodiment in which the present invention is shown as an improved form of a mechanism which is otherwise already 50 known.

In the form illustrated, the cross-head 1 is understood to be reciprocated from left to right in a suitable slideway by means of a short crank articulated by a connecting rod to the transverse pivot 2. The conveyer troughs are coupled to a second cross-head 3 by means of a transverse pivot 4. The drive from cross-head 1 both forwardly and rearwardly is transmitted to cross-head 3 through the intermediary of a strong compression spring 5 engaged between collars 6, 7, bearing against a shoulder 8 integral with cross-head 3, and a boss 9 detachably mounted on the tail 10 of cross-head 3 by means of a screw thread, the parts being locked by a grub screw 11, split pin or the like.

The collars 6, 7, are driven rearwardly and forwardly by internal shoulders formed on the casing 12 integral with the cross-head 1.

Now according to the present invention, a certain amount of "slogger" or loose motion is introduced between the two pivots 2, 4. This loose motion, in the form shown, is provided between the collars 6, 7, and the engaging faces of the casing 12. The drawing shows the parts in a mid position and the total amount of loose motion is represented by the two gaps *a* and *b*. In order that this amount of loose motion may be varied, the engaging 75 face of the casing 12 at one end is comprised by an adjustable threaded sleeve 13 received into the threaded end of the casing and adapted to be locked in any position to which it has been set by a lock nut 14.

With the above construction it will be realized generally that as the cross-head 1 moves to the right in the figure, after it has reached its maximum velocity and begins to decelerate, the cross-head 3 will be projected forward relatively to the cross-head 1 by an amount depending on the inertia of the moving parts of the conveyer and also upon the extent to which the spring 5 has been compressed. After receiving the amount of lead 90 permitted by the gaps *a* and *b*, it will then be suddenly decelerated owing to the engagement of the forward collar 6 with the collar 13 at a time when the forward velocity of the cross-head 1 is rapidly declining to zero.

Further, this deceleration dislodging the material will occur at a time when the mass of material is moving with a higher velocity than if the conveyer, coupled to the pin 4, had been constrained to follow the natural deceleration curve of pin 2; since in the absence of slogger the linear velocity of pin 2 will have fallen by a considerable amount before its rate of change of velocity, i. e. deceleration, reaches such a high value that the friction of the material in the trays is overcome. Thus, with the present invention, the dislodgment of the material occurs at a time when its kinetic energy ($\frac{1}{2}MV^2$) is much higher than is the case without slogger; the invention is thus equivalent to the provision of a crank of substantially increased length giving a substantially increased stroke to pin 2.

In the reverse direction, the initial movement of the cross-head 3 will correspond generally with that of cross-head 1 and have a sharp acceleration reaching a maximum at about one third of the stroke. After this point the cross-head 3 will move freely under its own inertia as the cross-head begins to decelerate, but as deceleration of the cross-head 1 commences early and lasts for an extended period on the reverse stroke the variation between the two speeds will not be so pronounced as in the forward stroke, and will be of no practical effect on the material.

It will be understood that the sudden deceleration on the forward stroke shifts the material in the conveyer and that the acceleration on the rearward stroke, being steadied or softened by being transmitted through the spring 5, is insufficient to dislodge the material in the conveyer.

From the above description it will be realized that the invention provides for a short deceleration at the end of the forward stroke by providing in the mechanism a certain amount of loose motion. It will also be realized that the inwardly-directed oppositely-facing shoulders of the casing 12 form driving abutments and that the outwardly-directed oppositely-facing shoulders of the boss 9 and thickened portion 8 rigid with the cross-head 3 comprise actuating shoulders or abutments; and that the floating members 6, 7, urged apart by the spring 5 comprise a resilient link whereby the drive is transmitted in both directions from a driving abutment to an actuating shoulder; and that the drive transmitted by the resilient link in both directions is only taken up by an actuating shoulder after a certain amount of loose motion on the part of a driving abutment by reason of the provision of the gaps *a*, *b*.

I claim:

1. A member to be interposed between the driving means and trough of a shaking conveyer, comprising relatively slidable elements connected respectively to the driving means

and to the trough, abutments slidable on one member, a coiled spring encircling such member and arranged between the abutments, and means on the respective elements for cooperating with the abutments to control the spring relation between the elements, said means constituting a lost motion with respect to the abutments.

2. A member to be interposed between the driving means and trough of a shaking conveyer, comprising relatively slidable elements connected respectively to the driving means and to the trough, abutments slidable on one member, a coiled spring encircling such member and arranged between the abutments, and relatively adjustable means on the respective elements for cooperating with the abutments to control the spring relation between the elements, said means constituting a lost motion with respect to the abutments.

3. An actuating means to be arranged between the power elements and the trough of a shaking conveyer, including a driving member and a driven member connected for relatively free limited play in the power direction, a spring carried by one of the members and responsive to relative movement of both members to take up the free play under the driving movement of the driving member and yield such free play to the driven member at the limit of driving action, and means intermediate the spring and driving and driven members to cause the yielding of the free play to the driven member to permit movement thereof free of the driving member and to the extent of such free play at a rate of travel substantially equaling the maximum rate of travel of the driving member.

4. A means for actuating the trough of a shaking conveyer from the power means, including a driving member, a driven member, said members being arranged for relatively free limited play in the direction of driving movement, a spring carried by one of the members, abutments carried at the respective ends of the spring, and means on the driving member and driven member to operate through the spring for taking up the free play between said members during driving action and yield that free play to the driven member at the limit of driving action, the relation of the means on said members permitting the driven member when moving under the free play permitted to move at a rate substantially equaling the maximum rate of the driving member.

5. A means for actuating the trough of a shaking conveyer from the power means, including a driving member, a driven member, said members being arranged for relatively free limited play in the direction of driving movement, a spring carried by one of the members, abutments carried at the

respective ends of the spring, and adjustable means on the driving member and driven member to operate through the spring for taking up the free play between said members during driving action and yield that free play to the driven member at the limit of driving action, the relation of the means on said members permitting the driven member when moving under the free play permitted to move at a rate substantially equaling the maximum rate of the driving member.

6. A means for actuating the trough of a shaking conveyer from the power means, including a driving member, a driven member, said members being arranged for relatively limited free play in the direction of driving movement, a spring carried by one of the members, abutments carried at the respective ends of the spring, and means on the driving member and driven member to operate through the spring for taking up the free play between said members during driving action and yield that free play to the driven member at the limit of driving action, the relation of the means on said members permitting the driven member when moving under the free play permitted to move at a rate substantially equaling the maximum rate of the driving member, the cooperation of said means and abutments providing a sharply defined deceleration of such driven member at the limit of such free play movement.

35 In testimony whereof I affix my signature.
